UNITED STATES PATENT OFFICE.

ALBERT F. BREITENSTEIN, OF NEW HAVEN, CONNECTICUT, ASSIGNOR TO THE GEOMETRIC TOOL CO., OF NEW HAVEN, CONNECTICUT, A CORPORATION.

ADJUSTABLE TAP.

Application filed October 3, 1921. Serial No. 504,960.

To all whom it may concern:

Be it known that I, ALBERT F. BREITENSTEIN, a citizen of the United States, residing at New Haven, in the county of New Haven and State of Connecticut, have invented a new and useful Improvement in Adjustable Taps; and I do hereby declare the following, when taken in connection with the accompanying drawings and the characters of reference marked thereon, to be a full, clear, and exact description of the same, and which said drawings constitute part of this application, and represent, in—

Fig. 1 a view in side elevation of my improved adjustable tap.

Fig. 2 a view thereof in front elevation.

Fig. 3 a view thereof in rear elevation.

Fig. 4 a view thereof in central longitudinal section on the line 4—4 of Fig. 2.

Fig. 5 a view thereof on the line 5—5 of Fig. 2.

Fig. 6 a detached view in side elevation of the tapered adjusting-head, with its diametrically slotted stem.

Fig. 7 a view thereof in front elevation.

Fig. 8 a detached view of the adjusting cross-piece.

My invention relates to an improvement in adjustable taps, the object being to produce a simple, compact, efficient and durable tap of comparatively few parts and constructed with particular reference to convenience, accuracy and stability of adjustment.

With these ends in view, my invention consists in an adjustable tap having certain details of construction and combinations of parts as will be hereinafter described and pointed out in the claim.

In carrying out my invention, as herein shown, I employ a tapered adjusting-head 10 having a stem 11 formed with a diametrical slot 12 receiving an adjusting cross-piece 13 connecting the stem 11 and hence the head 10 with an internally-threaded adjusting-collar 14 mounted upon the threaded shoulder 15 of the tap-body 16, which is formed, as shown, with six centrally intersecting radial slots 17 for the reception of as many dies or chasers 18, the slanting inner edges 19 of which are formed with coupling-slots 19 for the reception of complementary overhanging coupling-ribs 20 formed upon the head 10, whereby the chasers are coupled thereto and held in place thereby, as may be required in the use of the tap or to com-

pensate for wear. The overhanging ribs 20 of the head 10 converge from rear to front to conform to the taper thereof, while the inner edges of the chasers are cut at an angle and grooved to correspond to the pitch of the overhanging ribs 20, as clearly shown.

The adjusting-collar 14 aforesaid is formed with a forwardly extending sleeve 21 reaching over the cross-piece 13 and encircling the rear portion of the tap-body 16. The collar proper is formed at four equidistant points with spanner-holes 22, here shown as provided with hardened bushings 23. The inner end of the stem 11 of the head 10 is formed with a threaded bore 24 for the reception of a screw 25, the head 26 of which fits within the bore 27 of the hollow tap-shank 28. The said screw is encircled by a retracting-spring 29 impinging at its rear end upon the under face of the screw-head 26, and at its forward end upon a washer 30 resting upon an annular shoulder 31 located in the bore 27 of the shank 28. The outer ends of the slots 17 in the tap-body 16 are closed by means of a cap 32 secured in place by screws 33, whereby the chasers are held against forward displacement.

For locking the adjusting-collar 14 in any position in which it may be set, I employ a bronze shoe 34, set into a transverse notch in its threaded inner face and jammed upon the threads of the shoulder 15 of the tap-body 16 by means of a set-screw 35, as shown in Figure 3.

Normally, the tension of the retracting-spring 29 will hold the forward end wall of the slot 12 in the stem 11, against the forward edge of the adjusting cross-piece 13, the ends of the rear edge of which are also held by the spring against the forward face of the collar, as shown in Figure 4, whereby back-lash is taken up, and the chasers maintained in accurate predetermined adjustment.

If it is desired to compensate for wear or to increase the diameter of the hole threaded by the chasers 18, the set-screw 35 is loosened so as to release the adjusting-collar 14, which is now turned clockwise with the effect of positively forcing the adjusting cross-piece 13 forward, and thus positively forcing the head 10 forward, and to that extent expanding the cutting range of

the chasers by moving them radially outward. When the desired expansion of the chasers has been effected, the set-screw 35 is again turned home to bind the adjusting-
5 collar 14 upon the shoulder 15 of the tap-
body. Reversely, if it is desired, for any
reason, to contract the chasers 18, the collar
14 is loosened and turned counter-clock-
wise, whereby it is moved rearwardly upon
10 the shoulder 15, this rearward movement be-
ing accompanied by the concurrent rearward
movement of the head 10 and stem 11 and
adjusting cross-piece 13 under the pull of
the retracting-spring 29, this operation be-
15 ing also attended by the withdrawal or re-
traction of the chasers 18. The collar 14 is
now again locked by the screw 35. It will
thus be seen that by my invention, I am
enabled to compensate for wear, as well as
20 to adjust the chasers for various fits of
threads, my device being characterized by
the use of an adjusting cross-piece passing
diametrically through the stem of a tapered
adjusting-head and controlled by an adjust-
25 ing-collar, mounted upon the tap-body.

I claim:

In an adjusting tap, the combination with
the slotted body and hollow shank thereof,
of a tapered adjusting-head provided with
a stem having a diametric slot, chasers lo-
cated in the slots of the said body and coupled
with the said head for positive extension
and contraction thereby, an adjusting cross-
piece passing through the diametric slot in
the stem of the head, a collar threaded upon 30
the tap-body and co-acting with the said
cross-piece for positively moving the same
and hence the stem and head, forward, and
a retracting-spring located within the hol-
low shank of the tap-body and connected 40
with the stem of the head for exerting a
constant effort to draw the same rearward.

In testimony whereof, I have signed this
specification in the presence of two subscrib-
ing witnesses.

ALBERT F. BREITENSTEIN.
